United States Patent Office

Des. 215,683

Patented Oct. 21, 1969

215,683

HAIR CLIPPER

Herbert R. Carpenter, Chicago, Ill., assignor to Andis
Clipper Co., Racine, Wis., a corporation of Wisconsin

Filed Dec. 5, 1968, Ser. No. 14,819

Term of patent 14 years

Int. Cl. D28—03

U.S. Cl. D95—3

FIG. 1 is a view in three-quarter front perspective of a hair clipper embodying my new design.

FIG. 2 is a view thereof in plan on a reduced scale.

FIG. 3 is a view thereof in side elevation on the scale of FIG. 2.

FIG. 4 is an inverted plan view thereof on the scale of FIG. 2.

FIG. 5 is a view taken in cross section on the line 5—5 of FIG. 2.

FIG. 6 is a view thereof in rear elevation from the viewpoint of the line designated 6—6 in FIG. 2.

I claim:

The ornamental design for a hair clipper, as shown.
